DESIGN FOR A DRINK MIXER

James F. Barnes and Jean Otis Reinecke, Chicago, Ill., assignors to Scovill Manufacturing Company, Waterbury, Conn., a corporation of Connecticut

Application October 30, 1939, Serial No. 87,939

Term of patent 14 years

To all whom it may concern:

Be it known that we, James F. Barnes and Jean Otis Reinecke, citizens of the United States, residing at Chicago, in the county of Cook and State of Illinois, have invented a new, original, and ornamental Design for a Drink Mixer, of which the following is a specification, reference being had to the accompanying drawings, forming part thereof.

In the drawings:

Fig. 1 is a side elevational view of a drink mixer showing our new design.

Fig. 2 is a front elevational view of the same.

Fig. 3 is a rear elevational view of the same.

Fig. 4 is a top plan view of the same.

We claim:

The ornamental design for a drink mixer, as shown.

JAMES F. BARNES.
JEAN OTIS REINECKE.
